CLAIM

The ornamental design for a large, single deck, high wing airplane, as shown and described.

DESCRIPTION

FIG. 1 is a left side elevational view of a large, single deck, high wing airplane showing our new design, the right side elevation being a mirror image of this view;

FIG. 2 is a front elevational view thereof;

FIG. 3 is a rear elevational view thereof;

FIG. 4 is a top, plan view thereof; and,

FIG. 5 is a bottom view thereof.
